UNITED STATES PATENT OFFICE

ADALBERT BORNAND, OF LONDON, ENGLAND

TALKING MACHINE

Application filed September 24, 1926, Serial No. 137,588, and in Great Britain March 8, 1926.

My invention relates to a talking machine, the distinctive feature of which is that it comprises a box with lid in which can be shut up, while the apparatus is at rest, the various parts of same and on the bottom of which is fixed a frame for the motor as well as a socket carrying, while the apparatus is at rest, the diaphragm with the stylus and securing, while the said apparatus is running, by a hole into which its rear end may be fitted, the hollow arm designed to receive the diaphragm.

The accompanying drawings illustrate one manner of adapting for use the device provided by my invention. Fig. 1 shows a view on the horizontal plane; Fig. 2 shows a longitudinal section; Figs. 3 and 4 show plan and longitudinal sectional views of the lid removed, the latter view being taken on the line IV-IV of Fig. 3.

1 is a box-shaped casing of metal with a lid 2. On the bottom of the box are fixed a frame 3 for the motor and a socket of wood 4. As usual the motor consists of a spring drum 5 to be wound up at 6 and drives a vertical shaft 6, which bears the washer 7. It is between the said washer and the milled nut 8 that the talking machine record is placed. For braking the motion of the latter, a system of coupled rods 9 may be used. 11 represents the box containing the diaphragm and carrying the stylus. 12 is the tone arm which, when the apparatus is running, fits in the mouth 13 of the socket 4 and receives, at the other end, the box 11. 14 refers to a crank fitting onto the head 5 for the winding up of the motor.

The lid 2 shows both a projection 15 covering the washer 7 and a hole for the passage of the shaft 6. Like the talking machine record, this lid, therefore, is held in place against the washer 7 by the milled nut head 8. On the side opposite to the one showing the projection, the lid has also a groove 16 into which the rim 17 of the lid 1 gets engaged.

Having thus described my invention, I claim and desire to secure by Letters Patent:

1. In a talking machine, a box, a lid there-

for, a motor mounted in said box including a shaft, a washer on said shaft, said lid having an opening adapted to receive said shaft, and means adapted to clamp said lid against said washer, said means also being adapted to secure a phonographic record in position. 55

2. A talking machine as claimed in claim 1, characterized by the provision of means on the extremity of the lid remote from the shaft for preventing its outward displacement from the box. 60

In testimony whereof I affix my signature.

ADALBERT BORNAND.
